(1351) Review Bypass Tool for Smartkey, Bosnianbill, Jan. 13, 2021, youtube, internet, published: Sep. 1, 2018 (Year: 2018).*

Primary Examiner — Susan Bennett Hattan*Assistant Examiner* — Elizabeth S Ko(74) *Attorney, Agent, or Firm* — Haynes Befel & Wolfeld LLP; Andrew L. Dunlap(57) **CLAIM**

The ornamental design for a by-pass tool for door knobs, as shown.

DESCRIPTION

FIG. 1 is a top-front perspective view of a by-pass tool for door knobs showing my new design;

FIG. 2 is a top plan view thereof;

FIG. 3 is a cross-sectional view thereof along line 3-3 of FIG. 2;

FIG. 4 is a bottom plan view thereof;

FIG. 5 is a front elevation view thereof;

FIG. 6 is a rear elevation view thereof;

FIG. 7 is a left-side elevation view thereof; and,

FIG. 8 is a right-side elevation view thereof.

The invention is shown together with environmental structure in broken lines in FIGS. 1-8, the environmental structure forming no part of the claimed design.
